(57) **CLAIM**

The ornamental design for orthotics for limbs, as shown and described.

DESCRIPTION

FIG. 1 is a perspective view of orthotics for limbs in accordance with aspects of the present disclosure.

FIG. 2 is a first side view of the orthotics for limbs in accordance with aspects of the present disclosure.

FIG. 3 is a second side view of the orthotics for limbs in accordance with aspects of the present disclosure.

FIG. 4 is a front view of the orthotics for limbs in accordance with aspects of the present disclosure.

FIG. 5 is a rear view of the orthotics for limbs in accordance with aspects of the present disclosure.

FIG. 6 is a top view of the orthotics for limbs in accordance with aspects of the present disclosure; and,

FIG. 7 is a bottom view of the orthotics for limbs in accordance with aspects of the present disclosure.

Any subject matter shown in dashed lines, and any surfaces of the design not shown, including interior surfaces, form no part of the claimed invention.

1 Claim, 7 Drawing Sheets
